COMBINATION GAS-OIL BURNER
APPARATUS

Cyril Charles Young, Kansas City, Mo.

Application August 27, 1952, Serial No. 306,683

9 Claims. (Cl. 158—11)

1

This invention relates generally to combustion burner units and more particularly to a two-fuel burner unit capable of operating as a combination gas-oil burner apparatus.

According to the general principles of the present invention, a combustion chamber is provided which is adapted to burn one type of fuel such as fuel oil and a flame port is provided for the combustion chamber so that the oil fed flames will be directed outwardly of the combustion chamber through the flame port.

A flame spreader plate, or target plate as it is sometimes known, is positioned adjacent the flame port and is effectively interposed in the path of the flames exiting the flame port so as to spread the flames outwardly of the flame port.

Conduit means adapted to be connected to a source of gas fuel supply extend through the flame spreader plate and include a gas nozzle which is positioned outside of the combustion chamber and in protected, shielded relation with respect thereto. A second flame spreader plate, parallel to and spaced from the first mentioned flame spreader plate, spreads the flames from the gas nozzle outwardly.

The usual pilot burner and safety thermal cutoff element are provided adjacent the gas nozzle and in the space between the flame spreader plates.

It is an object of the present invention to provide a combination gas-oil burner apparatus wherein the gas burning means is adequately protected against oil fed flames.

Another object of the present invention is to provide a combination gas-oil burner apparatus wherein the gas burning elements of the apparatus are located outside of the oil combustion chamber.

Yet another object of the present invention is to provide a burner apparatus having a plurality of spaced apart flame spreaders with gas burning nozzle means disposed therebetween.

A further object of the present invention is to provide a combination gas-oil burner unit which will enjoy great stability in operation.

Many other features, advantages and additional objects of the present invention will become manifest to those versed in the art upon making reference to the detailed description which follows and the accompanying sheet of drawings in which a preferred structural embodiment of a combination gas-oil burner unit is shown by way of illustrative example only.

On the drawings:

Figure 1 is a side elevational view with parts

2

broken away and with parts shown in cross section of a combination gas-oil burner unit provided in accordance with the principles of the present invention; and

Figure 2 is a reduced cross-sectional view with parts shown in elevation taken substantially on line II—II of Figure 1.

As shown on the drawings:

A combination gas-oil burner unit is indicated generally at 10 and in the preferred embodiment herein shown, an annular vaporizer tray 11 is included which may be supplied with a vaporizable oil fuel through a conduit 12. It will be understood that the conduit 12 is connected to a suitable source of fuel oil (not shown). The annular vaporizer tray 11 constitutes the closed end of an annular combustion chamber 13 having an open end providing a flame port 14 and including radially spaced inner walls 16 and outer walls 17.

The inner walls 16 comprise a generally cylindrical sleeve 18 which extends upwardly beyond the open end of the annular combustion chamber 13 and which has a convergent tapered portion 19 at the other end thereof firmly engaging the inner annular edge 20 of the vaporizer tray 11.

The outer walls 17 comprise a cylindrical sleeve 21 having the edges at one end thereof received in a notched annular recess 22 provided in the outermost edge portions of the vaporizer tray 11. The other end of the sleeve 21 has its edge portions received in an annular recess 23 provided in one face of a cap ring 24. It will be understood that the central opening of the cap ring 24 defines the outer edge of the flame port 14 at the open end of the combustion chamber 13.

The sleeve 21 is provided with a plurality of apertures arranged in circumferentially spaced relation and aligned on vertically spaced rows.

In the preferred embodiment herein shown, three rows of apertures 26, 27 and 28 are provided. If desired, the lowermost row of apertures 26 may be made smaller than the other rows of apertures and the rows of apertures 27 and 28 may be made of successively larger size.

A generally cylindrical casing 29 surrounds the combustion chamber 13 and together with the sleeve 21 supports the cap ring 24.

A tubular baffle 30 extends through the center of the tray 11 and is spaced radially inwardly of the inner walls provided by the cylindrical sleeve 18. The tubular baffle 30 engages the tray 11 at the inner edge 20. The tubular baffle 30 is apertured as at 31.

At the upper end of the tubular baffle 30 and

the cylindrical sleeve 18 is provided a flame spreader plate 32, sometimes known as a flame target or a target plate. In this particular embodiment, the flame spreader plate 32 is formed as an annular member having a recess 33 in one face thereof seating the end of the cylindrical sleeve 18 and having an opening through the center thereof receiving the end of the tubular baffle 30.

A perforated ring 34 may be interposed between the sleeve 18 and the tubular baffle 30 so as to provide a restriction in an annular air flow passage 36 formed between the sleeve 18 and the tubular baffle 30. The sleeve 18 is also provided with circumferentially spaced apertures 37 which place the annular air flow passage 36 in communication with the combustion chamber 13.

A blower (not shown) discharges pressurized combustion supporting air into the conduit 38 whereupon the air will flow into the plenum chamber 39 formed by the cooperation of the casing 29 and the combustion chamber 13. It will be noted that air thus introduced into the plenum chamber 39 will flow through the apertures 31 in the tubular baffle 30 so that the air flow passage 36 will also function as a plenum chamber. Thus, the entire combustion chamber 13 is surrounded by a plenum chamber which extends around the combustion chamber 13 and which also extends through the center of the combustion chamber 13. It will be apparent that the apertures 26, 27 and 28 in the outer walls 17 and the apertures 37 provided in the inner walls 16 will admit combustion supporting air into the combustion chamber 13 so that oil vaporized in the tray 11 will burn in the combustion chamber 13 whereupon flames produced by such burning will be directed toward the flame port 14.

The flame spreader plate 32 extends radially outwardly so as to overlie the flame port 14 and the open end of the combustion chamber 13, thereby spreading any flames exiting from the flame port 14 outwardly.

Conduit means including a gas pipe 40 extend upwardly through the tubular baffle 30 and extend through the flame port 14 and through the center of the flame spreader plate 32. The gas pipe 40 is connected at one end to a T fitting 41 which, in turn, is coupled to a conduit 42 supplied with gas fuel from a source (not shown).

The T fitting 41 is plugged as at 43 so as to be supported on a stand 44. Additional support means in the form of a plate 46 may be provided on the other end of the T fitting to engage the conduit 38 which, in turn, underlies and supports the casing 29.

A gas nozzle 47 is carried on the end of the gas pipe 40 and is positioned outside of the combustion chamber 13 but adjacent the flame spreader plate 32 so as to be protected and shielded by the flame spreader plate from the oil fed flames exiting the combustion chamber 13 through the flame port 14.

A stem 48 extends through the center of the gas nozzle 47 and carries a second flame spreader plate 49 in spaced parallel alignment relative to the first mentioned flame spreader plate 32.

The gas nozzle 47 is arranged between the flame spreader plates 32 and 49 so that the flames emanating from the circumferentially spaced row of gas ports 50 will be spread outwardly by the second flame spreader plate 49.

A gas pilot burner 51 is connected to a pilot conduit 52 and is located adjacent the gas nozzle

41 in the zone lying between the flame spreader plates 32 and 49. The pilot conduit 52 extends parallel to the gas pipe 40 and is connected to an L fitting 53 which, in turn, is coupled to a conduit 54 in communication with a supply of gas fuel.

The thermal element 56 of a safety cut-off is positioned directly adjacent the pilot burner 51 and the gas nozzle 47 and is arranged to be heated by the pilot burner 51 under normal circumstances. It will be understood that the thermal element 56 is connected by suitable means indicated at 57 to a conventional cut-off in control of the gas supply to the gas conduit 42 so that extinction of the pilot burner 51 will result in the actuation of the cut-off, thereby insuring that no gas fuel will be supplied to the gas nozzle 47 unless such fuel will be ignited by the pilot burner 51.

Because of the advantageous structural location of the gas nozzle 47 between the flame spreader plates 32 and 49, it will be appreciated that the pilot burner 51 and the thermal element 56 are adequately protected and shielded by the flame spreader plate 32 against the oil fed flames exiting the combustion chamber 13 through the flame port 14.

Although various minor structural modifications might be suggested by those versed in the art insofar as the preferred structural embodiment herein described by way of illustrative example is concerned, it should be understood that I wish to embody within the scope of the patent warranted hereon all such modifications as reasonably and properly come within the scope of my contribution to the art.

I claim as my invention:

1. A combination gas-oil burner unit, comprising, a combustion chamber having a flame port, means supplying oil fuel to the combustion chamber, a pair of flame spreader plates adjacent said combustion chamber and disposed on respective parallel planes generally normal to the axis of said flame port, one of said plates adapted to spread the flames exiting the combustion chamber through said flame port, a gas nozzle positioned between said flame spreader plates, and means supplying gas fuel to said nozzle, the other of said plates adapted to spread the gas flames emanating from said nozzle.

2. A combination gas-oil burner unit, comprising, a combustion chamber having a flame port, a first flame spreader plate adjacent said port and arranged to spread flames passing out of said combustion chamber through said flame port, conduit means extending through said flame port and through said flame spreader plate, a second flame spreader plate disposed parallel to and spaced from said first flame spreader plate, a nozzle on the end of said conduit means and being positioned between said first and second flame spreader plates to direct a flame against the second spreader plate, means supplying oil fuel to the combustion chamber, and means supplying gas fuel to the conduit means.

3. A combination gas-oil burner unit, comprising, a combustion chamber having a flame port, an annular vaporizer tray on the bottom of said combustion chamber, means supplying oil fuel to the tray, a first flame spreader plate adjacent said flame port, conduit means extending through the center of said tray, through said flame port, and through said first flame spreader plate, a second flame spreader plate parallel to and spaced from said first plate, a nozzle on

said conduit means and positioned between said first and said second flame spreader plates, and means supplying gas fuel to the conduit means, whereby said nozzle will direct a gas flame against said second flame spreader plate.

4. A two-fuel burner unit comprising, an annular combustion chamber adapted to burn a vaporizable fuel, said combustion chamber having radially spaced inner and outer walls and being open at one end, said inner walls projecting beyond said open end and supporting a flame spreader plate which overlies the open end of said combustion chamber and is adapted to spread the flames emanating therefrom, conduit means extending through the center of said chamber and through said flame spreader plate, and a nozzle to burn a gaseous fuel and being connected to said conduit means, said nozzle being shielded from the flames of the combustion chamber by said flame spreader plate.

5. A combination gas-oil burner unit, comprising, a combustion chamber having a flame port, conduit means extending through said flame port and having a nozzle on the end thereof of outside of said combustion chamber, means supplying oil fuel to the combustion chamber, whereby oil fed flames are directed toward the flame port, means supplying gas fuel to the nozzle, whereby the gas fuel is burned outside the flame port, and a flame spreader plate between said nozzle and said flame port to insulate the nozzle against the oil fed flames and to spread the oil fed flames outwardly of the flame port.

6. A two-fuel burner unit comprising, an annular combustion chamber open at one end and adapted to burn a vaporizable fuel, means providing inner and outer radially spaced walls for said chamber, the inner walls projecting beyond the open end of said chamber, a flame spreader plate on said inner walls and overlying said open end of said chamber to spread flames exiting therefrom, a conduit means extending through said chamber and through said plate, and a nozzle adapted to burn a gaseous fuel and carried on the end of said conduit means and being shielded from the combustion chamber by said plate.

7. A combination gas-oil burner unit comprising an annular combustion chamber open at one end and having radially spaced inner and outer

10
15

walls, means supplying oil fuel to said combustion chamber, a casing surrounding said combustion chamber, the inner walls of said combustion chamber carrying a flame spreader plate overlying the open end of the combustion chamber, said casing together with said plate and said inner and outer walls forming a plenum chamber extending around the combustion chamber and extending through the center of the combustion chamber, said inner and outer walls of said combustion chamber having circumferentially spaced apertures therethrough admitting air from said plenum chamber to support the combustion of oil in said combustion chamber, conduit means extending through the center portion of the plenum chamber and extending through said flame spreader plate, means supplying gas fuel to the conduit means, and a nozzle on said conduit means shielded from said combustion chamber

20 by said flame spreader plate.

8. A combination gas-oil burner unit as defined in claim 7 and a second flame spreader plate parallel to and spaced from the said flame spreader plate to spread the flames from said nozzle outwardly.

9. In a combination gas-oil burner, a combustion chamber having a flame port, means supplying oil fuel to the combustion chamber, a gas nozzle adjacent the flame port but outside of the combustion chamber, means supplying gas fuel to the nozzle, and a flame spreader plate overlying the flame port and interposed between the nozzle and the combustion chamber to shield the nozzle from oil fed flames, and a pilot burner for said nozzle including a safety thermal cut-off element heated by said pilot burner, both said pilot burner and said safety thermal cut-off element being spaced adjacent the gas nozzle and being shielded from oil fed flames by the flame spreader plate.

walls, means supplying oil fuel to said combustion chamber, a casing surrounding said combustion chamber, the inner walls of said combustion chamber carrying a flame spreader plate over-

lying the open end of the combustion chamber, said casing together with said plate and said inner and outer walls forming a plenum chamber extending around the combustion chamber and extending through the center of the combustion chamber, said inner and outer walls of said combustion chamber having circumferentially spaced apertures therethrough admitting air from said plenum chamber to support the combustion of oil in said combustion chamber, conduit means extending through the center portion of the plenum chamber and extending through said flame spreader plate, means supplying gas fuel to the conduit means, and a nozzle on said conduit means shielded from said combustion chamber

20 by said flame spreader plate.

8. A combination gas-oil burner unit as defined in claim 7 and a second flame spreader plate parallel to and spaced from the said flame spreader plate to spread the flames from said nozzle outwardly.

9. In a combination gas-oil burner, a combustion chamber having a flame port, means supplying oil fuel to the combustion chamber, a gas nozzle adjacent the flame port but outside of the combustion chamber, means supplying gas fuel to the nozzle, and a flame spreader plate overlying the flame port and interposed between the nozzle and the combustion chamber to shield the nozzle from oil fed flames, and a pilot burner for said nozzle including a safety thermal cut-off element heated by said pilot burner, both said pilot burner and said safety thermal cut-off element being spaced adjacent the gas nozzle and being shielded from oil fed flames by the flame spreader plate.
